UNITED STATES PATENT OFFICE.

AUGUST SCHONHORST, OF ALTADENA, CALIFORNIA.

PHONOGRAPH TONE CHAMBER.

Application filed April 11, 1921. Serial No. 460,371.

To all whom it may concern:

Be it known that I, AUGUST SCHONHORST, a citizen of the United States, and resident of Altadena, in the county of Los Angeles, State of California, have invented new and useful Improvements in a Phonograph Tone Chamber, of which the following is a specification.

This invention relates to sound reproducing instruments, such as phonographs, and pertains especially to the tone chamber.

The primary object of this invention is to produce a device of this character which will improve the volume and quality of the reproduced sound so that the original tone is reproduced unimpaired. Another object of this invention is to provide details of construction whereby a simple compact and inexpensive structure is obtained.

These objects together with other objects and corresponding accomplishments are obtained by means of the embodiment of my invention illustrated in the accompanying drawing, in which:

Fig. 1 is a vertical section of my device; Fig. 2 is a front elevation looking at the mouth of the tone chamber; and Fig. 3 is a fragmentary section as seen on the line 3-3 of Fig. 1.

The tone arm of the phonograph is adapted to be connected to the elbow 4 of the tone chamber. The entire tone chamber according to my invention is preferably constructed of wood, and I prefer to construct the elbow section 4 of maple. Extending from the elbow is the chamber section of the device indicated by 5. This chamber section flares outwardly in the usual manner and is preferably made of spruce, the walls being graduated in thickness decreasing from the inner to the outer end of the chamber. This provides for increasing vibration of the chamber walls towards the mouth of the chamber.

Extending transversely across the chamber adjacent the mouth thereof is a partition wall 6 having formed therein a number of openings, in which are disposed auxiliary amplifiers 7. These amplifiers are preferably made of spruce, flare outwardly, and the walls thereof diminish progressively in thickness toward the mouth ends thereof.

In the chamber section adjacent the elbow are two diaphragms 8 of thin resilient material, preferably mica. These diaphragms are angularly disposed to one another and intersect as shown in Fig. 3. They do not close the chamber, but have a direction which in general is axial to the chamber. They may be secured in position by any suitable means, such as grooved strips 9 secured on the upper and lower walls, the mica being slipped into the grooves.

The operation of the chamber is obvious. Sound waves pass down through the elbow 4 and into the tone chamber section 5, impinging upon the mica diaphragms 8, but sliding thereover. The diaphragms are caused to vibrate and intensify the tone. As the waves advance toward the mouth of the horn, the walls of the chamber assist in intensifying the tone. Finally the sound waves pass through the auxiliary amplifiers, being further intensified. All of the parts of the chamber are so arranged, that no vibrations foreign to the natural quality of the tones are produced. Furthermore, none of the elementary vibrations of the sounds are intensified to any degree greater than others. There are no obstructions to pocket the air and confuse the sound.

What I claim is:

1. A device of the character described comprising a main outwardly flaring chamber, and a plurality of auxiliary chambers 85 of structure corresponding to said main chamber and disposed across said main chamber in proximity to the mouth thereof.

2. A device of the character described comprising a main outwardly flaring chamber, a partition wall extending across said main chamber in proximity to the mouth thereof and having a plurality of openings for auxiliary chambers, and a plurality of auxiliary chambers mounted in said partition wall and supported solely by said wall, said auxiliary chambers corresponding in structure to said main chamber.

In witness that I claim the foregoing I have hereunto subscribed my name this 2nd day of April, 1921.

AUGUST SCHONHORST.
